UNITED STATES PATENT OFFICE

LEWIS F. SMALL, OF BRAINTREE, MASSACHUSETTS

LAST

Application filed July 20, 1928. Serial No. 296,169.

This invention relates to lasts of that type in which the fore part is pivoted or hinged to the heel part so that the last may be collapsed to facilitate removal from the shoe in the process of manufacturing the latter.

The present invention has for its object to provide a last of the character described in which provision is made for a maximum movement of the fore part when the last is collapsed, and in which provision is also made for rendering the last practically solid, with the fore part and heel part practically immovable with relation to each other when in the shoe and subjected to blows or pressure in the process of manufacturing the shoe.

The invention further has for its object to provide a last of the character described in which all the parts of the last are connected together, so that when the last is removed from the shoe danger of any of the parts being lost or misplaced is avoided.

The invention further has for its object to provide a last of the character described, with a fore part having a metallic member which is pivoted to the heel part and a non-metallic sole member of wood or other suitable material which is detachably secured to the pivoted member, whereby the heel part, the pivoted member of the fore part, and a strut member inserted between the heel part, and the pivoted member of the fore part may be made of metal, and employed as a standard for lasts having non-metallic sole members of different sizes.

These and other features of the invention will be pointed out in the claims at the end of this specification.

Fig. 1 is a side elevation of a preferred construction of last embodying the invention;

Fig. 2, a plan of the last shown in Fig. 1;

Fig. 3, a side elevation of the last shown in Fig. 1 with the strut member withdrawn, preparatory to collapsing the last;

Fig. 4, a side elevation of the last shown in Fig. 1, showing the non-metallic sole member displaced from its operative position;

Fig. 5, a side elevation of a modified con-

struction of last embodying the invention, and

Fig. 6, a plan of the last shown in Fig. 5.

In the preferred construction of last shown in Figs. 1 to 4 inclusive, *a* represents the heel part and *b* the fore part.

The heel part *a* may and preferably will be made of metal, preferably aluminum, and is provided with the usual socket 10 for the reception of the spindle of the jack, not shown, upon which the last is placed in the manufacture of the shoe.

The fore part *b* is preferably provided with two members 12, 13, which are detachably secured together by screws 14 or otherwise. The lower member 12 may be designated the sole member and the upper member 13 may be designated the instep member.

The instep member 13 is hinged or pivotally secured to the heel part *a*, for which purpose it is provided with a substantially circular extension or ear 15, which fits a curved socket 16 in the front portion of the heel part and is secured to the heel part by a pivot pin 17.

The instep member 13 is provided with a substantially vertical wall 18 and with a horizontal wall 19, which co-operate with a substantially vertical front wall 20 of the heel part *a* to form a recess 21 between the heel part *a* and the fore part *b*, for the reception of an insert member 23, which is provided with a curved front wall 24 and with a substantially vertical rear wall 25, which co-operate with the substantially vertical walls 18, 20, of the fore part *b* and heel part *a* to cause the insert member 23 to function as a strut member and substantially prevent movement of the fore part with relation to the heel part, when said fore part is subjected to blows or pressure in the process of manufacturing the shoe on the last.

The insert member 23 is movably attached to either the fore part *b* or to the heel part *a* and in the present instance is shown as hinged or pivoted to the heel part by a pivot pin 26 extended through a substantially circular lug or ear 27 extended from the insert member into a curved socket 28 in the heel part in a manner well understood.

Provision is made for locking the insert member when in the recess 21 which may be accomplished in any suitable manner, as for instance, by means of a pin 29 extended through the insert member 23 into a socket in the heel part.

Additional means may be provided for resisting pivotal movement of the fore part with relation to the heel part under the influence of blows or pressure upon the fore part, and to this end the sole member 12 of the fore part may be provided with a projection 30 which enters a socket 31 in the portion 32 of the front wall of the heel part below the point at which the fore part is hinged or pivoted to the heel part.

The projection 30 may be made in the form of a curved plate or bar which is inserted into a curved slot 33 made in the non-metallic member 12 of the fore part, said plate and slot being substantially concentric with the hinge pin 17.

By reference to Fig. 1, it will be observed that pivotal movement of the fore part with relation to the heel part under the influence of blows imparted to the fore part or pressure applied thereto in the process of manufacturing a shoe on the last, is resisted by the locked strut member 23 and also by the locked fore part *b*.

It will be observed that the insert member when locked in its operative position, shown in Fig. 1, practically renders the movable parts of the last immovable under the influence of blows and imparts to the last having a fore part hinged to the heel part the functions of a solid or one-piece last while in use, and yet enables the said last to be collapsed a maximum amount, when it is desired to remove the last from the shoe.

When it is desired to collapse the last, the locking pin 29 is removed and the insert member 23 is then turned upwardly out of its recess, and may be turned upwardly into a substantially vertical position as represented in Fig. 3, or it may be turned further into a horizontal position and rest upon the heel part *a*.

In either position, the insert member does not offer any opposition to the pivotal movement of the fore part into its collapsed condition in which the fore part is inclined with relation to the heel part. It will also be observed that when the insert member 23 is withdrawn from its recess, it remains attached to the heel part and remains in operative relation to the heel and fore parts, and avoids liability of the insert member being lost, which would render the last useless to the shoe manufacturer until a duplicate of the lost insert member was obtained from the last manufacturer.

It may be preferred to make the last of metallic and non-metallic material as above described with reference to Figs. 1 to 4, but

it is not desired to limit the invention in this respect, as the invention may be embodied in a last in which the fore part, heel part, and strut member are of wood or other non-metallic material as represented in Figs. 5 and 6.

In the construction shown in Fig. 5, the fore part *b* is composed of one piece of non-metallic material, such as wood, is pivoted at 17 to the heel part *a*, and has its upper surface curved downwardly toward the pivot pin 17 and is provided with a substantially vertical rear wall 25, which engages the substantially vertical front wall 20 of the heel part.

The insert member 23 is pivotally secured to the heel part by the hinge 43 and its front end is locked to the fore part by the pin 44, which is removed when it is desired to collapse the last.

When the insert member is locked to the fore part by the pin 44, the substantially vertical rear wall 25 of the insert member co-operates with the substantially vertical front wall 20 of the heel part to cause the insert member to function as a strut and resist pivotal movement of the fore part under pressure or blows.

The insert member 23 is shown as pivoted to the heel member but it is not desired to limit the invention in this respect as it is evident it can be hinged to the fore part.

From the above description it will be seen that the parts of the collapsible last are connected together and are constructed and arranged to function as a solid last in their operative position, and to permit a maximum collapsing of the fore part with relation to the heel part when it is desired to remove the last from the shoe.

What is claimed is:

1. In a last, in combination, a heel part, a fore part pivoted to the heel part and constructed to form with the heel part a recess in the upper surface of the last, an insert member pivoted to said heel part and having a rear wall engaging a front surface of the heel part to transmit blows on the fore part of the last directly to the heel part independently of the pivot and movable into and out of said recess with the heel part and fore part in their non-collapsed or operative positions and forming a strut between said fore part and said heel when in said recess to resist pivotal movement of the fore part, and means for locking said insert member in said recess.

2. In a last, in combination, a metal heel part, a fore part having a metal member hinged to said heel part and constructed to form with the latter a recess in the upper surface of the last, and having a non-metallic sole member detachably secured to said metal member, a metal insert member movable into and out of said recess and attached

to said heel member, and means for locking said insert member when in said recess to form a strut member.

3. In a last, in combination, a heel part, a fore part pivoted to the heel part and constructed to form with the heel part a recess in the upper surface of the last, an insert member pivoted to said heel part and movable into and out of said recess with the heel part and fore part in their non-collapsed or operative positions and forming a strut between said fore part and said heel when in said recess, means for locking said insert member in said recess, and a member for rigidly connecting the fore part with the heel member below the pivot for the fore part.

4. In a last, in combination, a heel part, a fore part pivoted to the heel part and constructed to form with the heel part a recess in the upper surface of the last, an insert member attached to one of said parts and having a rear wall engaging a front surface of the heel part to transmit blows on the fore part of the last directly to the heel part independently of the pivot and movable into and out of said recess with the heel part and fore part in their non-collapsed or operative positions to form a strut member between the fore and heel parts when in said recess to resist pivotal movement of the fore part, and means for locking said insert member to one of said parts when in said recess.

5. In a last, in combination, a heel part provided with a substantially vertical front wall, a fore part hinged to said heel part and provided with a substantially vertical wall and a substantially horizontal wall co-operating with the front wall of the heel part to form a recess in the upper surface of the last between the heel part and said fore part, an insert member hinged to one of said parts and movable into and out of said recess with the heel part and fore part in their non-collapsed or operative positions and provided with a substantially straight wall co-operating with one of the said vertical walls to enable the insert member to function as a strut between said fore and heel parts when in said recess, and means for locking said insert member in said recess.

6. In a last, in combination, a heel part, a fore part having an instep member hinged to the said heel part and constructed to form with the latter a recess in the upper surface of the last and having a sole member detachably secured to said instep member, an insert member movable into and out of said recess with the fore part and heel part in their non-collapsed or operative relation and constructed to form a strut member when in said recess, and means for locking said insert member when in said recess.

7. In a last, in combination, a heel part, a fore part pivoted to the heel part and co-operating with the latter to provide a recess

in the upper surface of the last, and an insert member connected with one of said parts and pivoted to be movable into and out of said recess with the fore part and heel part in their non-collapsed or operative relation, said insert member and said recess having cooperating surfaces arranged with respect to the pivot to transmit blows on the fore part to the heel member independently of the pivot and to resist pivotal movement of the fore part to thereby permit the insert member to form a strut member in said recess.

8. In a last, in combination, a heel part, a fore part pivoted to the heel part and cooperating with the latter to provide a recess in the upper surface of the last, and an insert member pivoted to the heel part adapted to fill the recess and form the instep portion of the last, said heel and fore parts and said insert member having cooperating substantially vertical walls by which blows on the fore part are transmitted to the heel part independently of the pivot, said insert member being movable into and out of said recess with the fore part and heel part in their non-collapsed or operative relation.

9. In a last, in combination, a heel part, a fore part pivoted to the heel part and co-operating with the latter to provide a recess in the upper surface of the last, an insert member pivoted to one of said members and movable into and out of the said recess with the heel part and fore part in their non-collapsed or operative positions and having a rear wall engaging a front surface of the heel part when in said recess to transmit blows on the fore part of the last directly to the heel part independently of the pivot, and means for locking the insert member in said recess.

In testimony whereof, I have signed my name to this specification.
